UNITED STATES PATENT OFFICE.

WILLIAM D. STANGER, OF MERCHANTVILLE, NEW JERSEY.

DIE FOR FORMING METAL STAYING-STRIPS.

1,044,283.

Specification of Letters Patent. Patented Nov. 12, 1912.

Application filed March 14, 1912. Serial No. 683,846.

To all whom it may concern:

Be it known that I, WILLIAM D. STANGER, a citizen of the United States, residing at Merchantville, county of Camden, and State of New Jersey, have invented a new and useful Improvement in Dies for Forming Metal Staying-Strips, of which the following is a full, clear, and exact description, reference being had to the accompanying drawings, which form a part of this specification.

The object of my invention is to produce an improved punch or die for the manufacture of a certain type of metallic strips such as are employed for staying box corners, and for other purposes. The type of strip which I desire to produce is that old and well known type, illustrated, for example in Design Patent No. 25,580 of June 2d, 1896, in which eyelets are formed integral with the strip by punching out therefrom sets of burs, prongs, or pointed projections, each set of projections surrounding an orifice and adapted to be pressed into the material of the box or other article and clenched. Heretofore the manufacture of strips containing eyelets of this character has been effected by means of two dies, one having a series of holes and the other a corresponding series of punches, both the holes and punches being circular in cross section, and each punch being provided with a pyramidal shaped end forming a series of cutting edges between which edges the punch is either flat or concaved. With such punching mechanism, it has been found practically impossible to form the projections with any close approximation to accuracy or uniformity, inasmuch as the edges of the projections frequently tear near the base thereof in such manner as to form an undercut, thereby materially weakening the projections. Frequently, also, minute supplemental pointed projections are formed between the main projections.

The specific object of the present invention is to so construct the dies that the punches will form the projections without tearing the edges at the base thereof, and without the formation of any functionless and objectionable supplemental projections between the main projections. I have discovered that the object can be substantially attained and a more nearly perfect eyelet formed by a simple expedient. This expedient consists of retaining the holes in one

die of a circular form and in making the punches of the other die of polygonal form in cross-section, the points of the projections being preferably of pyramidal form as heretofore and with straight sides between the cutting edges. Another advantage secured by this form of punch is that the projections will be bent out from the strip at substantially right-angles thereto instead of curling backward as heretofore, thereby facilitating their insertion into the material of which the box or other article is made.

My invention will be more clearly understood by reference to the accompanying drawings, in which—

Figure 1 is a perspective view of a part of a metal strip with eyelets of the character produced by my invention; Fig. 2 is a perspective view of the two members of my improved die; Fig. 3 is an enlarged vertical sectional view through one of the punches and its corresponding hole; Fig. 4 is a plan view of one of the punches.

a is a part of one die, the same containing the holes *b*, which are circular in cross-section and of substantially the diameter of the eyelets to be formed.

c is a part of the other die, the same carrying the punches *d*, which, as shown, are square in cross section, *e* representing the four sides and *f* the four corners or cutting ribs. The distance from one corner to the diametrically opposite corner of a punch is approximately equal to the diameter of its corresponding hole, so that when the punch reciprocates in the corresponding hole, the corners of the punch will nearly or quite touch the wall of the hole. Each punch is tapered at the end to form four cutting ribs *g* connected by the four flat triangular faces *h*.

In Fig. 1 is illustrated a strip provided with the eyelets formed by the co-operation of the punches and holes aforesaid.

While I have illustrated a punch with four flat sides it will be understood that the number of sides depends upon the number of projections that it is desired to form in the eyelet, the only requirement being that the punch shall be provided in its body portion, with flat sides as distinguished from a circular contour.

I do not herein claim the punch *per se* but only the same combined with a round hole, both elements being necessary to the

production of a strip free from the objections hereinbefore enumerated.

Having now fully described my invention, what I claim and desire to protect by Letters Patent is:

1. In mechanism for forming eyelets in metal strips, the combination with a die having a series of round holes, of a complementary die forming a corresponding series of punches, each of which has a tapered end and a body which is polygonal in cross section.
2. In mechanism for forming eyelets in metal strips, the combination with a die having a series of round holes, of a complementary die having a corresponding series of punches, each of which has a body provided with cutting edges and a pyramidal end provided with cutting edges constituting a continuation of the cutting edges

of the body, the entire periphery of the body of the punch comprising a series of flat faces connecting the cutting edges.

3. In mechanism for forming eyelets in metal strips, the combination with a die having a series of round holes, of a complementary die having a corresponding series of punches, each of which has a body which in cross-section is of regular polygonal shape forming longitudinal equi-spaced cutting ribs and a pyramidal end having cutting edges alining with the cutting ribs of the body and tapered to a point.

In testimony of which invention, I have hereunto set my hand, at Philadelphia, on this 12th day of March, 1912.

WILLIAM D. STANGER.
